Aaron Harris

By his Atty. Wm. Smith

United States Patent Office.

AARON HARRIS, OF LAPORTE, CALIFORNIA.

Letters Patent No. 98,257, dated December 28, 1869.

IMPROVEMENT IN HYDRAULIC NOZZLES.

The Schedule referred to in these Letters Patent and making part of the same.

To all whom it may concern:

Be it known that I, AARON HARRIS, of Laporte, county of Plumas, and State of California, have invented a new and improved "Hydraulic Nozzle;" and I do hereby declare that the following is a full, clear, and exact description of the same, reference being had to the accompanying drawings, and letters marked thereon.

The principle object of my invention is to provide a nozzle for hydraulic mining, where it becomes necessary to throw streams of water of various sizes, and of greater or lesser force, against the bank of earth to be watered, although my device may be employed on fire-engines.

My invention consists in forming a transverse slot near the end of the nozzle, in which a gate is placed, having a circular opening, in which different-sized rings are placed, to increase or decrease the volume of the stream, without shutting off the water at the fountain-head.

In the drawings—

Figure 1 is an elevation of my nozzle.

Figure 2 is a plan, with adjustable spray-ring, for fire-engine hose.

Figure 3 is a sectional elevation.

Figure 4, a plan of gate.

The remaining figures are different views of rings.

To enable others skilled in the art to make and use my invention, I will proceed to fully describe its construction and operation.

I construct my nozzle in the form of a cylinder, with slightly flaring end, for the attachment of the hose.

The end of the nozzle is provided with a flange, A, through which I make a transverse slot, B, for the gate C.

The gate is attached to an arm or lever, D, by a pin, and the end of the arm works upon a pin in a lug cast to the nozzle, so that it may be lifted from the nozzle, for the introduction of the different-sized rings E E, and perforated disk or spray-ring, E', to reduce or increase the size or volume of the stream of water, or send it in form of spray into a burning building.

The outer circumference of the rings are uniform in size, but are provided with a different-sized bore, and set in the recess or seat of the gate, breasting the

course of the stream, in which position it is held, with the gate against a shoulder, near the end of the nozzle, by a screw-coupling, F.

The construction of the gate and slot is such, that by unscrewing the coupling and raising the lever, the gate and ring are easily lifted from the nozzle, for a ring having a larger or smaller bore, and that without shutting off the stream of water passing through the hose, however great in force or velocity; and no water will pass out through the slot, as the velocity is so great that the suction or drawing in of the air will entirely prevent the escape of water through the opening.

In the common hydraulic nozzle, different sizes of pipe were used to reduce or increase the size of the stream, which rendered it necessary, in order to make the change, to shut off the fountain-head, which often-times is approached through deep snow, and at the top of a high bluff, and requiring the time of one man an hour or more to accomplish it. Consequently, much greater risks were run by the hydraulic-miner in approaching near the bank to cut it down, without changing the size of the stream.

Many frightful accidents and deaths have occurred in this manner; but by my device the diameter of the stream may be changed almost instantly, and a smaller stream thrown against the bank of earth, at a greater distance and with greater force, without stopping the stream and approaching too near to danger.

Having thus described my invention,

What I claim, and desire to secure by Letters Patent, is—

1. The transverse slot B, in the nozzle, through which the gate is raised or lowered, for adjusting the rings, without stopping the flow of water through the nozzle, substantially as and for the purpose described.

2. The adjustable gate C, provided with a ring-seat, C', rings E E, and spray-ring E', which are held, when in position, against the shoulder of the nozzle, by the screw-coupling F, as described.

In testimony whereof, I have hereunto set my hand and seal.

AARON HARRIS. [L. S.]
